UNITED STATES PATENT OFFICE

111,973

DESIGN FOR A GAME BOARD

Minnis R. Jeffers, Bullsgap, Tenn.

Application June 2, 1938, Serial No. 77,534

Term of patent 3½ years

To all whom it concern:

Be it known that I, Minnis R. Jeffers, a citizen of the United States, residing at Bullsgap, in the county of Hawkins and State of Tennessee, have invented a new, original, and ornamental Design for a Game Board, of which the following is a specification, reference being had to the accompanying drawing, forming part thereof.

I claim:

The ornamental design for a game board, as shown.

MINNIS R. JEFFERS.
